UNITED STATES PATENT OFFICE.

WILLIAM H. THOMAS, OF JENKINTOWN, PENNSYLVANIA.

DESIGN FOR A FENCE-POST.

SPECIFICATION forming part of Design No. 26,363, dated December 1, 1896.

Application filed October 28, 1896. Serial No. 610,365. Term of patent 7 years.

To all whom it may concern:

Be it known that I, WILLIAM H. THOMAS, a citizen of the United States, residing at Jenkintown, in the county of Montgomery and State of Pennsylvania, have invented and produced a certain new and original Design for Fence-Posts; and I do declare the following to be a full, clear, and exact description of the invention, such as will enable others skilled in the art to which it appertains to make and use the same.

My invention relates to a design for a fence-post. It relates to the entire configuration of the fence-post.

My invention relates particularly to the fence-post as illustrated in the accompanying drawing, in which the figure is a perspective view of a fence-post embodying my design.

The leading features of my design appear in the following description.

1 represents the rectangular post, having a pointed top 2. The lower end of the post is formed with a transverse semicircular recess 3, the depending parallel edges of which form tapering ears 4, extending outwardly and downwardly to the plane horizontal base-plate 5.

Having thus fully described my design, what I claim as new, and desire to secure by Letters Patent of the United States, is—

The design for a fence-post, substantially as herein shown and described.

In testimony whereof I hereunto affix my signature in presence of two witnesses.

WILLIAM H. THOMAS.
